INVENTOR.

Joseph A. Rayder

BY

Alfred T. Bratton

ATTORNEY.

UNITED STATES PATENT OFFICE.

JOSEPH A. RAYDER, OF PHILADELPHIA, PENNSYLVANIA, ASSIGNOR TO ROBERT M. HILANDS, OF PHILADELPHIA, PENNSYLVANIA.

CURTAIN OR SHADE FIXTURE.

Application filed February 28, 1923. Serial No. 621,750.

To all whom it may concern:

Be it known that I, JOSEPH A. RAYDER, a citizen of the United States, residing at Philadelphia, in the county of Philadelphia and State of Pennsylvania, have invented a new and useful Curtain or Shade Fixture, of which the following is a specification.

This invention relates to brackets and the like for removably supporting rollers and analogous articles, and it has more particular reference to devices for mounting curtain or shade spring rollers relative to window, door or other frames.

The primary object of my invention is to provide a curtain or shade roller fixture fabricated from a single piece of suitable material, in combination with a locking member therefor which automatically retains the fixture in properly squared relation relative to the roller axis at all times, while securely holding said roller against accidental displacement.

Another object of this invention is to furnish a curtain or shade roller fixture of the character referred to which is simple and cheap to manufacture and at the same time neat and attractive in design and appearance.

With the foregoing and other objects in view my invention consists in the novel formation and combination of parts hereinafter fully described and more specifically defined by the subjoined claims.

In the further disclosure of the invention reference is to be had to the accompanying sheet of drawings forming a part of this specification, and in which like characters of reference designate the same or corresponding parts in all the views.

Figure 1, is a detail side elevation of the angle bracket for receiving the revolving pin end of the curtain or shade roller with the locking rosette in applied position.

Figure 2, is a similar side elevation of the angle bracket for receiving the squared end of the curtain or shade roller spring tension trunnion with the assembled locking rosette in section for the sake of clearness.

Figure 3, is a fragmentary detail of the angle bracket shank taken at right angles to the preceding showings.

Figure 4, is a face view; and

Figure 5, is a side view of the locking rosette hereinafter more fully described.

Referring more in detail to the drawings

each angle bracket 6, 7 consists of a length of suitable gauge wire providing a shank 8 having a screw-threaded end 9 and a frontal part 10 bent substantially at right angles to the said shank 8. The free end of the wire is 60 forwardly bent at an angle of approximately thirty degrees to the horizontal thus providing a protrusion 11, and said frontal part 10 and inclined protrusion 11, are disposed in direct axial alignment with the 65 aforesaid shank 8.

In the case of the angle bracket 6 the extreme forward end of the inclined protrusion 11 is curled back upon itself to provide a loop or eye 12 in which the shade roller 70 revolving pin is journaled in the well known manner. On the other hand the forward and longer portion of the inclined protrusion 11, in the case of the angle bracket 7, is turned back upon itself in parallel and 75 axial aligning relation relative to said protrusion at 13 to provide an inclined tongue 14. This inclined tongue 14 has its extreme free end 15 upwardly turned approximately 80 parallel to the aforesaid frontal part 10 thus providing an entry for the squared or rectangular end of the shade or curtain roller 85 spring tension trunnion, indicated by the dotted section 16 showing in Figure 2.

The locking rosette 17 is of truncated 85 trumpet section with a basal flange 18 having a plurality of stamped out prongs or spurs 19 therein, while the opposed or outer end of said rosette 17 is radially fluted at 20 for cooperative engagement with diametri- 90 cally opposed offsets or teeth 21 provided for the purpose on the shank 8 of each of the aforesaid angle brackets 6 or 7.

From the foregoing it will be apparent that in use the shade or curtain roller is 95 inserted in place by firstly putting the revolving pin thereof in the loop or eye 12, then inserting the spring tension trunnion 16 in the entry opening 22 and moving the rectangular or squared part thereof downwardly between the extreme free end 15 and frontal part 10 until the parallel flat sides of said trunnion seat snugly between the inclined protrusion 11 and tongue 14. Thus 100 it will be readily understood that the spring tension trunnion 16 will be held snugly in place with the effective avoidance of any possibility of the same riding out of its seat, while the curtain or shade roller will be firmly held against accidental movement 105 110

other than its normal rotation, and any danger of its displacement is avoided. Still further it will be readily seen that when the angle brackets 6, 7 are screwed 5 into the framework of a window or doorway the offsets or teeth 21 by cooperating with the radial flutings 20 on the outer ends of the locking rosettes 17, will force the prongs or spurs 19 thereon into said framework. As a result of this cooperation 10 the aforesaid offsets or teeth 21 will traverse the radial flutes 20—ratchet fashion—and any back motion be prevented. Thus it will be obvious that when the angle 15 brackets 6, 7 are once correctly mounted or fixed in place they will be securely retained properly squared relative to the axis of the curtain or shade roller.

It will of course be understood that slight 20 variations in the design of the angle brackets 6, 7 may be effected without departing from the spirit and scope of the subjoined claims.

Having described my invention what 1 25 claim as new is:—

1. A curtain or shade roller bracket comprising a shank having a screw thread at one end, said shank being formed with radial offset teeth and a downwardly bent 30 frontal part having an inclined protrusion the free end whereof is turned upon itself to provide a looped head, in combination with a truncated rosette, said rosette being provided with radial flutes at its outer end 35 for cooperation with the aforesaid shank teeth, and integral spurs at its inner end for impingement into the surface to which the bracket is attached.

2. A curtain or shade roller bracket comprising a shank having a screw thread at 40 one end, said shank being formed with radial offset teeth and a downwardly bent frontal part having an inclined protrusion the free end whereof is turned upon itself to provide a looped head, said inclined protrusion being disposed at an angle of thirty 45 degrees from the horizontal, in combination with a truncated rosette, said rosette being provided with radial flutes at its outer end 50 for cooperation with the aforesaid shank teeth, and integral spurs at its inner end for impingement into the surface to which the bracket is attached.

3. A curtain or shade roller bracket comprising a shank having a screw thread at 55 one end, said shank being fabricated with diametrically opposed offset teeth and a downwardly bent frontal part and inclined protrusion, the free end whereof is turned upon itself to provide a tongue parallel to 60 said protrusion and terminating in an upturned free end parallel to the frontal part, said inclined protrusion and tongue being disposed at an angle of thirty degrees below 65 the horizontal and forming a seat for the curtain or shade roller spring tension trunnion, in combination with a frontal rosette, said rosette being provided with radial flutes at its outer end for cooperation with the aforesaid shank teeth, and integral spurs on 70 its inner basal portion for impingement into the surface to which the bracket is attached.

In testimony whereof I affix my signature this 10th day of February, 1923.

JOSEPH A. RAYDER.
